(Cl. 246—38)

1

This invention relates to coded track circuit signaling systems for railways, and more particularly to a coded track circuit organization employing code pulses of different polarity and embodying suitable means for preventing false signal indications in the event of a failure of the insulated joints at the signal locations.

In certain applications of coded track circuits to the control of automatic block signals and the like, it becomes expedient to employ code receiving means responsive to code pulses of different polarity. For instance, in the interests of obtaining more uniform decoding response under variable ballast conditions, for better shunting, and for other purposes, it is desirable to employ code pulses of alternate polarity at different time spaced intervals for operating a magnetic stick type of code following track relay at different code rates for different signal indications, as disclosed for example in the prior application of F. X. Rees, Ser. No. 466,151, filed November 19, 1942.

In a coded track circuit organization of this character, in which the code following track relay means responsive to the polarity of code pulses is associated with the forward track section in advance of the signal, and in which code transmitting means acts to apply code pulses of different polarity to the track rails of the rear track section on the opposite side of the insulated joints, it can be appreciated that a failure of these insulated joints will render the code pulses applied to the rear track section effective to operate the track relay means for the forward track section; and under certain conditions may cause a false coding operation of this track relay means which will result in the display of an improper indication of the associated signal. In other words, where the signal indications are governed by code pulses of different polarities, broken down insulated joints may cause dangerous false clear signal indications.

The primary object of this invention is to provide simple and effective means for preventing such improper signal indications in such a polarized coded track circuit organization in the event of the failure of the insulated joints at a signal location.

Generally speaking, and without attempting to define the nature and scope of the invention, protection against false signal indications in the event of a failure of the insulated joints associated with a signal is obtained by rendering the code pulses applied to the rear track section ineffective to operate the code following track relay

2

means for the forward track section in a manner to give a caution or clear indication of this signal in the absence of legitimate signal clearing code pulses in such forward track section. Considered more specifically, when a signal has been put to stop by the passage of a train, the code following track relay for the forward track section is disconnected or isolated during the time each code pulse is being applied to the rear track section, so that the signal cannot be improperly cleared by the code pulses from the rear track section, in spite of a failure of the insulated joints, and remains at stop until legitimate signal control pulses are received, whereupon the code following track relay is connected directly to the forward track section independently of the application of code pulses to the rear track section, and may be operated at any desired code rate without interference.

20 In a coded track circuit organization of this character, it may be expedient to provide inverse or "off" code pulses for approach lighting the signal or for other purposes; and provision is also made in accordance with this invention to afford broken down joint protection when such an inverse code is used. More specifically, it is proposed that the inverse code pulses shall all be of the same polarity, and since the code following track relay of the adjacent section requires opposite polarities alternately to effectively operate it, these inverse code pulses could not possibly cause its false operation even if the insulated joints between the two track sections were broken down.

35 An organization of this character affords the desired broken down joint protection for normal train movements; but when a clear indication of a signal should be changed to caution or stop by removal of the legitimate signal control pulses without shunting the code following track relay, as in the case of a back-up train movement, or operation of an outlying switch in another track section, then the clear indication of the signal may be maintained under broken down joint conditions at least until a train approaching that signal puts it to stop by its shunting action acting past the broken down insulated joints. Accordingly, it is proposed in accordance with this invention to employ different code rates for the clear indication in adjoining track sections adjacent each signal, so that code pulses applied to the track section in the rear of a signal cannot give a clear indication of that signal under broken down joint conditions, because such code pulses are not of the proper rate. With such an ar-

arrangement of different clear code rates for alternate blocks, whenever the legitimate clear code pulses for a signal are cut off, this signal will give the proper restrictive indication.

Various other objects, attributes, operating characteristics and advantages of the invention will be in part apparent, and in part pointed out as the specific embodiment of the invention are later described.

In the accompanying drawings,

Fig. 1 illustrates in a diagrammatic and conventional manner a stretch of track for a multiple track railroad equipped with block signals having their indications governed in accordance with the rate of code pulses of different polarity, and provided with broken down joint protective means in accordance with this invention;

Fig. 2 is an explanatory diagram illustrating the general nature of the signal control codes employed in the organization of Fig. 1;

Figs. 3A and 3B, when arranged end to end, illustrate the same type of system shown in Fig. 1, with inverse or "off" code pulses for approach lighting control; and

Figs. 4A and 4B are explanatory diagrams illustrating the signal control and inverse code pulses employed in the organization of Figs. 3A and 3B.

The illustration of the electrical circuits in the accompanying drawings has been simplified by indicating by arrows and the symbols (+) and (-) connections to the opposite terminals of batteries or other suitable sources of current; and in general, the parts and circuits have been shown in these drawings in the conventional manner, more with the view of facilitating an explanation and understanding of the operating characteristics and functions of the invention, than for the purpose of showing in detail the particular structures and arrangements of parts preferably employed in practice.

One specific embodiment of the invention is illustrated in Fig. 1 in connection with the control of conventional three-aspect automatic block signals 2 and 3 for a multiple track railroad by code pulses of alternate polarity of different clear and caution code rates. For simplicity, it has been assumed that each block between successive signals comprises one track section; but it should be understood that suitable cut sections, with means for relaying or repeating the code, may be employed. The normal direction of traffic is from left to right.

Referring to the relays and circuits associated with the signal 2 in Fig. 1 as typical of the apparatus at each signal location, the code following track relay 2TR is a two-position polar ray of the magnetic stick type having no spring bias, and acts to operate and hold its armature and contact fingers illustrated conventionally in one extreme position or the other in response to the momentary energization of its energizing circuit with one or the other polarity of current. This relay is preferably constructed in accordance with recognized practice to be quick acting, and thus responds to current pulses of short duration. The operation of the contact finger 12 of this track relay 2TR governs the energization of the two halves of the primary of a decoding transformer 13, one secondary of which is connected to a slow-release home relay 2H through the contacts of another contact finger 14 of this track relay performing the functions of rectifying contacts to cause energization of this relay 2H by uni-directional current pulses in response to the coding op-

eration of this track relay. Another secondary 15 of the decoding transformer 13 is connected by a tuned circuit and full-wave rectifier 16 to a slow-release distant relay 2D, in accordance with the well known practice. This arrangement of code responsive means, which is merely typical of an organization suitable for this purpose and which may take other forms, operates in the well known manner familiar to those skilled in the art to maintain energization of the home relay 2H in response to a coding operation of the track relay 2TR at any of the selected rates, but to maintain energization of the distance relay 2D only when the track relay 2TR is operated at some particular clear code rate for which the tuned circuit and decoding equipment is constructed or adjusted. For reasons explained more fully hereinafter, the distant relay 2D for the signal 2 requires for its energization one particular clear code rate, such as 180 cycles per minute, while the distant relay 3D for the signal 3 next in advance, and likewise the distant relay for the signal (not shown) in the rear of signal 2 requires for its energization a different clear code rate, such as 120 code cycles per minute.

The signal 2 may be of any suitable type governed in accordance with recognized practice by the home and distant relays 2H and 2D so as to indicate clear when both relays 2H and 2D are energized, caution when the relay 2H alone is energized, and stop when these relays 2H and 2D are both deenergized. In the arrangement shown, the signal 2 is assumed to be a simple color light signal having green, yellow, and red lamps G, Y and R for clear, caution and stop indications. These lamps are lighted by circuits controlled by front and back contacts 17 and 18 of the relay 2H and 2D, in a manner readily understood from the drawings.

Considering now the code transmitting means associated with the signal 2 and typical of all signal indications, a transmitter relay 2CTP is arranged to be connected through front and back contacts 19 respectively of the home relay 2H by obvious circuits to coding contacts operating at the clear and caution code rates, assumed to be 120 and 75 times per minute in the case of signal 2, by suitable code oscillators or motor operated coders shown diagrammatically and designated 120CT and 75CT.

Transmitter relay 2CTP operates the armature and contacts of a repeater or chopper relay 2XCT to different positions as the transmitter relay is energized and deenergized. In the specific arrangement illustrated, this chopper relay 2XCT is a two-position polarized relay of the magnetic stick type without any gravity or spring bias, and is provided with two windings respectively energized through front and back contacts 20 of the transmitter relay 2CTP. The energization of the lower winding of this chopper relay 2XCT is assumed to cause movement of its contact fingers to the left-hand position as shown, and the energization of the other winding moves the contact fingers to the other dotted line position. The track battery 1B for the track section 1T in the rear of signal 2 is connected through resistor 1R and through front and back contacts 21 and 22 of the transmitter relay 2CTP, which act as pole changing contacts, in series with contacts closed in the opposite positions of the contact fingers 23 and 24 of the chopper relay 2XCT, in a manner to provide pulses of opposite polarity as the transmitter relay 2CTP is energized and deenergized at the code rate then effective, such code pulses hav-

ing a relatively short duration corresponding with the operating time of the chopper relay 2XCT.

Considering now the provision made for broken down joint protection, the code following track relay 2TR for the forward track section 2T in advance of signal 2 is connected to the track rails of this track section by circuit connections including front and back contacts 25 of the transmitter relay 2CTP and contacts closed with the contact finger 26 of the chopper relay 2XCT in corresponding extreme positions, so that while the transmitter relay 2CTP and the chopper relay 2XCT are momentarily out of corresponding positions during the time interval the track battery 1B is connected to the rear track section 1T, the track relay 2TR is isolated or disconnected. For example, with the transmitter relay 2CTP and the chopper relay 2XCT in the position shown in Fig. 1 subsequent to the transmission of a code pulse of one polarity (assumed to be positive), and with the track battery 1B disconnected from the rear track section 1T, the track relay 2TR is connected across the track rails of the forward track section 2T through the back contact 25 of the transmitter relay 2CTP and a contact finger 26 of the chopper relay 2XCT in the left-hand position. As soon as the transmitter relay 2CTP is energized to apply the next code pulse of opposite polarity to the rear track section 1T, its back contact 25 opens the circuit connections for the track relay 2TR, and isolates this track relay, so to speak, until the chopper relay 2XCT has operated to cut off the track battery 1B by movement of its contact fingers to the dotted line position, whereupon track relay 2TR is again connected to its track section through the front contact 25 of the transmitter relay 2CTP and the contact finger 26 of the chopper relay 2XCT in the dotted line position.

In short, during each of the time intervals that the track battery 1B is connected to the rear track section 1T, the track relay 2TR is disconnected from the forward track section 2T by the operation of the contacts 25 and 26 of the relays 2CTP and 2XCT, so that in spite of any failure of the insulated joints, code pulses applied to the rear track section 1T cannot operate the track relay 2TR under such conditions.

These contacts 25 and 26 of the transmitter relay 2CTP and the chopper relay 2XCT are shunted by a front contact 27 of the distant relay 2D; and consequently, when this distant relay 2D is energized, code following track relay 2TR is connected directly to the track section 2T, and may be operated at any desired code rate independently of code pulses applied to the rear track section 1T.

A block signal system using signal control codes of alternate polarity at different code rates, as diagrammatically illustrated in Fig. 2, operates to govern the signal indications in the same general manner as the usual rate code system. Under normal conditions and with no trains present, the code pulses of alternate polarity transmitted over the track rails in each block are spaced at time intervals corresponding with the clear code rate, which is preferably the same for every other block and different for adjacent blocks; and the coding operation of the code following track relay of each signal, such as the track relay 2TR, at the clear code rate energizes the home and distant relays 2H and 2D to cause the associated signal 2 to indicate clear.

Assuming now that a train passes signal 2

under these normal conditions, the shunting action of the wheels and axles of this train stops the coding operation of the track relay 2TR, leaving its contact fingers 12 and 14 in the last operated position; and consequently, the home relay 2H and the distant relay 2D both release to cause the signal 2 to indicate stop. Under these conditions, with the front contact 27 of the distant relay 2D open, the track relay 2TR is disconnected or isolated during the time intervals, when code pulses are applied to the rear track section 1T, by the operation of the contacts 25 and 26 of the transmitter relay 2CTP and the chopper relay 2XCT.

Assume now that the insulated joints at signal 2 are broken down by the movement of this train, and that the wheel shunt of the train in question is removed while the train still occupies the block protected by the signal 2, as for example, because the train has advanced beyond the insulated joints at a cut section or beyond a point where there is a broken track rail. It can be appreciated that the track relay 2TR under such broken down joint conditions could be intermittently energized improperly by the code pulses applied to the rear track section 1T, first at the caution code rate to energize relay 2H, and then upon the energization of this relay 2H at the clear code rate to energize the distant relay 2D, thereby giving a false clear indication for the signal 2. If the wheel shunt is removed because the train advances out of the block 2T past the signal 3, the failure of the insulated joints may give an improper clear indication for signal 2 instead of the proper caution indication, particularly if legitimate caution code pulses are not transmitted toward the signal 2 on account of some failure of decoding equipment.

In accordance with this invention, however, such improper coding operation of the track relay due to a failure of the insulated joints cannot occur, because the track relay is isolated at the time code pulses are applied to the rear track section, and will be energized only by legitimate code pulses received over its own track section.

In this connection, it should perhaps be pointed out that under broken down joint conditions at signal 2, for example, the wheel shunt of any following train approaching this signal is likely to stop coding operation of the track relay 2TR and put the signal 2 to stop before the train reaches it; but a clear indication of signal 2 at the entrance to an occupied block, or at the entrance to a block next in the rear of an occupied block, which may occur under broken down joint conditions without protective features of this invention, represents an unsafe condition, which is not obviated merely because the train puts the signal to stop in its face. This is because a train is not provided with a safe braking distance from such a stop signal to the hazard ahead. Thus, for reasons of safety it is necessary that a caution signal indication be given at the signal next in rear of a stop signal, regardless of the cause for which such signal is at stop.

Assuming normal operating conditions, when the train in question passes signal 3 out of the block 2T protected by the signal 2, and legitimate caution code pulses are transmitted toward the signal 2, the track relay 2TR is energized as soon as one of these legitimate code pulses is out of step, so to speak, with the operation of the transmitter relay 2CTP and the chopper relay 2XCT, so as to exist during the time in which code pulses are not being applied to the rear track section

¹T and track relay 2TR is effectively connected with the track rails of the track section 2T. Although these legitimate caution code pulses in the forward track section 2T are created by coding contacts nominally operating at the same caution code rate as the coding contacts 75CT governing the transmitter relay 2CTP, on account of unavoidable variations in manufacture or adjustment, these different coding contacts will not continue to open and close at precisely the same instant for any substantial length of time, even though these contacts should happen to be operating synchronously at the instant that the wheel shunt is removed. Further, since the code pulses employed with this invention are relatively short as compared with the time spacing between them, as indicated roughly in diagrams of Fig. 2; and since the track relay 2TR is disconnected or isolated from the rails for such a short time interval, a relatively small difference in the exact synchronous operation of the different coding contacts permits the intermittent energization of the track relay 2TR.

After one or more operations of the track relay 2TR by such legitimate code pulses, the home relay 2H is energized and closes its front contact 19 to initiate operation of the transmitter relay 2CTP at the 120 clear code rate. Under these conditions, the track relay 2TR is momentarily isolated 240 times per minute, while the legitimate code pulses are momentarily applied to the track section 2T twice for each interval at the caution 75 code rate, or 150 per minute. The net result is what may be termed a beat code condition, under which the track relay 2TR is intermittently energized at recurrent intervals at the caution code rate, with one code pulse occasionally blanked out because it occurs at the time this track relay is isolated. Such intermittent operation of the track relay 2TR is sufficient to maintain the home relay 2H energized, this relay having the usual slow releasing characteristic and being sufficiently long in its release time to maintain its armature in the attracted position for the blank intervals in the regular coding operation of the track relay 2TR at the caution code rate.

Thus, under normal operating conditions and where legitimate caution code pulses are transmitted at signal 2, the home relay 2H is energized to cause the signal to indicate caution; but the contacts 25 and 26 of the transmitter relay 2CTP and the chopper relay 2XCT continue to isolate the track relay 2TR at the particular instants when code pulses at the 120 caution code rate are applied to the rear track section 1T. Consequently, even if the insulated joints at the signal 2 should be broken down, improper coding operation of the track relay 2TR at the clear code rate and an improper clear indication of the signal 2 cannot be caused by code pulses for the rear track section 1T, either alone or in combination with the legitimate caution code pulses in the forward track section, since the code pulses from the rear track section never act on the track relay of the forward track section. In short, failure of the insulated joints at signal 2 cannot cause this signal to display an improper indication.

Assume now that the train in question advances and legitimate code pulses of the clear code rate are transmitted toward the signal 2. In the preferred arrangement shown, the clear code for block 2T is at the 180 code rate different from the 120 code rate for the clear code for the

¹T and hence for the reasons previously considered, there will be intermittent operation of the track relay 2TR by a number of pulses at the clear 180 code rate without interference by the operation of the transmitter relay 2CTP and the chopper relay 2XCT. This energizes the distant relay 2D, whereupon the front contact 27 of this relay closes to connect the track relay 2TR directly to the track section 2T independently of the operation of the relays 2CTP and 2XCT.

In this way, normal operating conditions are restored after a train movement, provided that legitimate signal control codes are received.

The protection against broken down insulated joints afforded by this invention has been discussed in connection with the movement of a train in the normal direction of traffic, which puts each signal to stop in turn by shunting its track relay, since these are the circumstances when the proper indication of each signal is essential to protect such train. However, it may be desirable in some situations to cause signals to indicate caution for a back-up train movement, or where an outlying switch is involved, by removal of the normal legitimate codes. For this reason, in the preferred embodiment of the invention illustrated, different clear code rates are employed for adjoining blocks, with the same clear code used in every other block. With this arrangement, if the legitimate 180 clear code for track section 2T governing the signal 2, for example, should be removed in connection with a back-up train movement or by operation of a switch or the like, as distinctive from an effective wheel shunt in track section 2, the distant relay 2D is automatically deenergized, regardless of broken down joint conditions, because this distant relay 2D requires for its energization a coding operation of the track relay 2TR at the 180 rate; and the code pulses applied to the rear track section 1T are at a different 120 code rate.

This deenergization of the distant relay 2D and the opening of its front contact 27 renders the contacts 25 and 26 of the transmitter relay 2CTP and the chopper relay 2XCT effective to cut off or isolate the track relay 2TR at the particular times any code pulses are applied to the rear track section 1T. Therefore, if all legitimate code pulses toward the signal 2 are cut off, the coding operation of the track relay 2TR ceases and the home relay 2H, as well as the distant relay 2D releases, putting signal 2 to stop and changing the code rate for the rear track section 1T to the proper caution indication for the signal (not shown) in the rear of signal 2. If, however, legitimate caution code pulses are being transmitted toward signal 2, then the home relay 2H is maintained energized under beat code conditions, and the signal gives the proper caution indication.

Thus, with different clear code rates in every other block in accordance with the preferred embodiment of the invention, any removal or change in the rate of legitimate signal control codes transmitted under normal clear conditions will govern the signals accordingly, in spite of any failure of the insulated joints.

In the foregoing discussion, the protective features for broken down insulated joints have been discussed in connection with train movements, since if no trains are present, the indications of the signals are not essential from the standpoint of protecting traffic. Insulated joints, however, may for some reason deteriorate and fail under normal coding conditions without any train move-

ment, and while the indications displayed by a signal under such circumstances is not material, it may be pointed out that the track relay 2TR, for example, is in effect under such conditions subjected to short code pulses of alternate polarity at different code rates supplied by different coding contacts and transmitter relays 2CTP and 3CTP. Generally speaking, the combination of short code pulses of alternate polarity at both 120 and 180 code rates, tends to produce a variable coding operation of the track relay 2TR, which is likely to cause the distant relay 2D to release, dependent upon its slow releasing characteristics, the general effect of the code combination in question being to operate the track relay temporarily first at the 120 rate and then at the 180 rate. If the distant relay 2D should release under these conditions, the opening of its front contact 27 isolates the track relay 2TR from the influence of the code pulses for the rear track section 1T, leaving the code pulses in the forward track section 2T effective to govern the relay 2D without interference. The resultant energization of the relay 2D and closure of its contact 27 again renders the track relay 2TR subject to combined effect of the 120 and 180 codes, thereby again releasing relay 2D. In other words, dependent upon the operating characteristics of the various relays and other conditions, a failure of the insulated joints under normal coding conditions without any train movement will ordinarily result in an intermittent change or pumping action between clear and caution indications of the signal. Such erratic operation of the signal, while of no significance from the standpoint of protecting train movements, attracts the attention of the engineers of passing trains to the abnormal conditions. In this connection, however, the failure of insulated joints are effectively detected or betrayed under ordinary circumstances, because the train approaching the signal puts it to stop in its face.

A coded track circuit of the type contemplated, which employs relatively short pulses of alternate polarity, provides a regular coding operation of the track relay independent of variations in battery voltage, ballast resistance and the like, since the back and forth movement of the armature of the track relay is determined by the time spacing of the code pulses, and is not materially affected by the degree of energization of the track relay under different ballast conditions and battery voltage. Also, the relatively short pulses are necessarily of a higher peak voltage than if maintained for a longer time interval, and tend to break down the resistance of any film on the trackway and give better shunting performance. Further, a polar relay of the magnetic stick type without any spring bias can generally be arranged to have greater sensitivity than a biased polar track relay, so that operating energy may be transmitted with less losses over longer track circuits.

Broken down joint protection for inverse codes.—In connection with the approach lighting of signals, control of the protective devices at highway crossings, and for similar purposes, it is sometimes desirable to provide what is conveniently termed inverse or "off" code pulses in conjunction with the signal controlling driven code pulses; and in the type of coded track circuit contemplated, it is advantageous to employ relatively short pulses for such inverse or "off" code control. If such inverse code pulses of alternate polarity are employed, and are of suffi-

cient intensity to operate a code following relay at the end of a track section in the rear of a signal, it can be appreciated that, if the insulated joints at such signals should be broken down, such inverse code pulses are likely to cause a coding operation of the code following track relay governing the signal, thereby under certain conditions giving the improper signal indication.

Figs. 3A and 3B illustrate the same arrangement shown in Fig. 1, supplemented by code transmitting and receiving means for inverse code pulses for approach lighting control, together with protection against broken down insulated joints in accordance with this invention for such an organization.

Referring to the apparatus at signal location 3 in Fig. 3B as typical of the various signal locations of this modified form of the invention, it will be seen that the same apparatus is provided as in Fig. 1, with the addition of certain means which is employed in connection with the transmission and reception of inverse codes. The track relay 3TR is associated with the track section 3T and is isolated therefrom by the front and back contacts 100 and 101 of relay 3CTP and 3XCT, when these contacts are out of corresponding positions in the same manner as previously described. The front contact 102 of relay 3D is similarly employed to shunt the isolating contacts 100 and 101. However, the track relay 3TR is normally connected to the track rails of the section 3T through a contact 103 of inverse code timing relay 3AXCT and a front or back contact 104 of an inverse code transmitting relay 3ATCP. Whenever a driven code pulse is received of a particular polarity, it causes the transmission of a momentary inverse code pulse through the proper control of the inverse code transmitting relay 3ACTP and associated timing relay 3AXCT which is controlled by front and back contacts 105 of relay 3ACTP.

At the leaving end of the rear track section 2T, the code transmitting relay 3CTP and its associated timing relay 3XCT operate to put driven code pulses on the track section 2T in the same manner as described in connection with Fig. 1, but in addition to such apparatus, an inverse code receiving track relay 2ATR of the two-position magnetic stick type is employed so as to be operated to one position by the reception of an inverse code pulse, and to be operated to the opposite position in accordance with the transmission of the following driven code pulse. This inverse code receiving track relay 2ATR is provided with front and back repeater relays 2AFP and 2ABP which are neutral relays with slightly slow releasing characteristics, so as to be maintained picked up between successive energizations as the result of the operation of relay 2ATR responsive to the reception of inverse code pulses.

The green, yellow and red lamps of the signal 3 are controlled in accordance with the position of the home and distant relays 3H and 3D the same as in Fig. 1, but these lamps are illuminated only when a train approaches the signal 3 and deenergizes the relay 2ABP. This is effected by including back contact 106 of relay 2ABP in the energizing circuits for these lamps, it being understood that normally inverse code is being received so that back contact 106 is normally opened.

Let us now assume normal conditions and consider how driven and inverse codes are transmitted through the track section 2T. Assuming that a driven code of the 120 code rate is being

properly received at signal 3 over the track section 3T, the relay 3H is picked up, so that the code transmitting relay 3CTP is connected through front contact 126 to the coder 180CT. Also, the distant relay 3D is energized to maintain through its front contact 102 a circuit connection for the track relay 3TR to the track section 3T independently of the operation of the transmitter relay 3CTP and its repeater relay 3XCT supplying driven code pulses to the rear track section 2T, so that the track relay 3TR may follow the code in the forward track section 3T without interference.

Considering the operation beginning at the particular time when the contacts of the coder 180CT next close to energize the transmitter relay 3CTP, as indicated by the line a—a in the diagram of Fig. 4A, a driven code pulse is applied to the rear track section 2T from the track battery 2B through a series limiting resistance 2R, front contacts 107 and 108 of transmitter relay 3CTP, and polar contacts 109 and 110 of the relay 3XCT in the left-hand position shown. At the same time, the front contacts 108 and 112 of the transmitter relay 3CTP act to connect the inverse code following track relay 2ATR across a selected portion of the limiting resistance 2R, so that the voltage drop caused by the driven code pulse supplies a momentary energizing current for the inverse code track relay 2ATR to restore its contact 113 to the right-hand dotted line position. This restoring circuit connection for the relay 2ATR may be traced from the left-hand side of the resistor 2R, front contact 108 of relay 3CTP to right-hand side of track relay 2ATR, winding of this track relay and front contact 112 of relay 3CTP to the adjustable connection to the resistor 2R. Also, the energization of the transmitter relay 3CTP closes its front contact 111 to energize the upper winding of relay 3XCT and shifts its polar contacts 109 and 110 to the right and terminate the driven code pulse in the same manner previously discussed.

Referring now to Fig. 3A, the reception of this driven code pulse at the other end of the track section 2T energizes the code following track relay 2TR, which at the time under consideration is connected to the track section 2T through a front contact 27 of the distant relay 2D, polar contact 115 of relay 2AXCT to the right and front contact 114 of inverse code transmitter relay 2ACTP. With the arrangement of circuit connections and polarities assumed for the particular organization illustrated, the driven code pulse under consideration shifts the polar contact 12 of the track relay 2TR from the position shown to the left, and opens the circuit then closed and readily traced on the drawings for energizing the inverse code transmitter relay 2ACTP. The de-energization of this relay 2ACTP and operation of its front contact 118 causes energization of the lower winding of the relay 2AXCT to shift its contact 115 to the left from the position shown to provide a connection with the inverse code track battery 2BB. At this time, however, front contact 114 of the relay 2ACTP is open, so that the battery 2BB is not connected to the track rails to provide an inverse code pulse.

In other words, a driven code pulse of one particular polarity, corresponding with that associated with the energization of the driven code transmitter relay by closure of its coding contacts in the particular arrangement shown, prepares a circuit connection for the inverse code

track battery by operation of the relay 2AXCT, but does not actually complete such circuit and transmit an inverse code pulse.

These operations just described occur while the transmitter relay 3CTP is energized by the closure of its associated coding contacts 180CT, corresponding with what may be termed the beginning of the "on" period of a driven code. When the coding contacts 180CT open and the transmitter relay 3CTP in Fig. 3B is deenergized, a driven code pulse of the other polarity is applied to the track rail track section 2T through back contacts 107, 108 of this transmitter relay until the polar contacts 109 and 110 of the relay 3XCT are shifted back to the position shown by energization of the lower winding of this relay 3XCT. At this time the front contact 112 of the transmitter relay 3CTP is open and disconnects the resistor 2R from the inverse code track relay 2ATR, so that the driven code pulse of this other polarity does not affect the inverse code track relay. However, when this driven code pulse ceases and the polar contacts 110 and 119 of the relay 3XCT assume the left-hand position, the inverse code following track relay 2ATR is connected across the track rails of the track section 2T ready to respond to any succeeding inverse code pulse.

The reception of this driven code pulse at the signal 2 energizes the track relay 2TR through back contact 114 and front contact 27 so that its contacts are again operated to the right. The closure of contact 12 in a right-hand position again energizes the relay 2ACTP so that the upper winding of the relay 2AXCT is energized through front contact 118 of relay 2ACTP. This causes contact 115 of relay 2AXCT to be operated to the right, but during this time of response of the contact 115, a circuit has been made to connect the battery 2BB momentarily across the track section 2T through front contact 114 of relay 2ACTP.

Such inverse code pulse applied to the track section 2T obviously occurs following the reception of the driven code pulse actuating the track relay 2TR, and since the driven code pulse has ceased, back contact 112 of relay 3CTP is closed and polar contacts 119 and 110 of relay 3XCT are in a left-hand position, so that the inverse code receiving track relay 2ATR is connected across the rails of the track section 2T ready to be energized by the inverse code pulse created by the operation of the relay 2ACTP and 2AXCT. This causes the contact 113 of relay 2ATR to be again operated to the left.

In this way, the transmission of driven code pulses of one polarity causes the inverse code track relay 2ATR to be operated to a particular position, such as its right-hand position; and the reception of the inverse code pulses, which are always of the same polarity and which follow the succeeding driven code pulse of the opposite polarity, causes the actuation of the relay 2ATR to its other or left-hand position. Thus, an inverse code pulse is transmitted during alternate time space periods between the driven code pulses for actuating the inverse code track relay 2ATR, which is restored by a local circuit to a different position during the other time space periods. This continued back and forth operation of the contact finger 113 of the inverse code track relay 2ATR obviously causes the relay 2ABP to be picked up to close its front contact 120 and allow the approach control relay 2ABP to also be picked up.

Although this operation specifically describes the transmission of an inverse code during the presence of a driven code of the 180 code rate in the track section 2T, it is to be understood that a similar operation occurs during the transmission of driven codes of the 75 code rate. These two different conditions have been indicated in the diagrams of Figs. 4A and 4B to show the relative operations of the code transmitting relays and the transmission of the inverse code pulses with respect to the driven code pulses. Although the 120 code rate has not been indicated in the diagram of Fig. 4A, it is to be understood that a similar operation occurs in the track sections 1T and 3T and other similar track sections where a different clear code rate of 120 is preferably used.

When a train enters the track section 2T, further transmission of the inverse code pulses in the manner above described ceases, and the contact finger 113 of the track relay 2ATR stays in the dotted line position to which it is restored by the intermittent energization of the transmitter relay 3CTP and continued application of driven code pulses to the track section 2T ahead of the train in question. The energizing circuit for the approach relay 2ABP is thus maintained open, instead of intermittently closed; and after a suitable release time sufficient to span the time intervals normally intervening between the successive driven code pulses, the back contact 106 of this approach relay 2ABP closes to provide approach lighting of the signal 3 in the well-known way.

The approach control afforded by inverse codes and shown as employed for approach lighting in the particular organization illustrated, may also be used for approach locking and other purposes; and in the interests of checking against failure of the restoring circuit, the relay 2AFP governing at its front contact 120 the energizing circuit for the approach control relay 2ABP, is preferably employed as shown, so that the approach control relay 2ABP will be deenergized, regardless of the particular position in which the contact finger 113 of the track relay 2ATR may happen to stop.

In connection with certain applications of inverse code for approach control purposes, the inverse code transmission in a track section is discontinued by suitable control, as distinctive from the shunting action of a train in such track section; and it is important that there should be no false self-coding operation of the inverse code following track relay due to the presence of a stray potential. Accordingly, in the organization of this invention, the polarities for the driven and inverse code pulses are preferably chosen as indicated, so as to provide for the same polarity of energization of the track rails by an inverse code pulse as for the particular driven code pulse during which the inverse code following track relay 2ATR is restored by its local circuit to one of its positions. With this preferred arrangement of polarities, any stray potential on the track rails of the track section 2T, which is of a polarity capable of simulating inverse code pulses in the energization of the relay 2ATR, will be of a polarity to change the flow of current through the resistor 2R causing restoration of the relay 2ATR to its other position.

In other words, a stray potential of a polarity and strength suitable for operating the track relay 2ATR to its left the same as a legitimate inverse code pulse, will be in a direction to neutralize or overpower the battery 2B, and thus

reduce the flow of current through the resistor 2R and prevent restoration of said relay 2ATR to its other right-hand position. Accordingly, the contact finger 113 of the relay 2ATR would stay in the position shown, and relay 2AFP releases to open its front contact 120 and in turn drop approach control relay 2ABP.

As above mentioned, each track relay, such as track relay 3TR in Fig. 3B, for example, is isolated during the transmission of each driven code pulse in the next adjacent track section to the rear while the front contact 102 of the distant relay 3D is open. In other words, the track relay 3TR is protected against the false operation from driven code pulses in the rear track section 2T the same as explained in connection with Fig. 1.

It will be appreciated that the track relay 3TR must be operated to opposite positions alternately in order to effect any operation of its associated decoding apparatus. Although the inverse code pulses in the rear track section 2T will occur at a time during which the track relay 3TR is not isolated from the rails of the track section 3T by the contacts 100 and 101 of relays 3CTP and 3XCT, such inverse code pulses cannot cause its operation to opposite positions alternately since the inverse code pulses are always of the same polarity.

In brief, this form of the invention provides, in addition to broken-down joint protection by isolation of the track relay from the driven code pulses in the track section next to the rear, broken-down joint protection for inverse code pulses by reason of the fact that such inverse code pulses are of one polarity and can only operate the track relay to one position, in which it will remain unless legitimate code pulses are received over its own track section. For these reasons, it is believed that this invention provides an automatic block signaling system which employs driven code pulses of alternate polarity with distinctive rates, together with inverse code pulses for approach lighting and the like, and which has adequate broken-down joint protection.

Having thus described two specific embodiments of the present invention, it should be understood that these forms are selected to facilitate in the description of the invention rather than to limit the number of forms which it may assume; and it is to be further understood that various modifications, adaptations and alterations may be applied to the specific forms shown to meet the requirements of practice, without in any manner departing from the spirit or scope of the present invention.

What I claim is:

1. In a coded track circuit signaling system for railroads, a forward track section separated from a rear track section by insulated joints, a signal governing the passage of traffic from the rear track section into the forward track section, code transmitting means associated with said signal for applying distinctive code pulses to said rear track section, a code following track relay normally connected across the rails of said forward track section, isolating means effective during the application of each code pulse to the rear track section by said code transmitting means for disconnecting said track relay from said forward track section, and means acting in response to the intermittent operation of said track relay for governing the indications of said signal and for rendering said isolating means ineffective.
2. In a coded track circuit signaling system for railroads having adjacent track sections sepa-

rated by insulated joints, a signal for governing traffic from a rear track section into a forward track section, a code receiving track relay associated with said forward track section and normally connected thereto, decoding means controlled by the intermittent operation of said track relay for governing the indications of said signal, a code transmitting means governed by said decoding means and acting to apply code pulses of different selected rates to said rear track section, and means governed by said code transmitting means and effective during the application of each code pulse to isolate said track relay from said forward track section, and thereby render it immune from code pulses from said transmitting means in the event said insulated joints should become broken down.

3. In a coded track circuit signaling system for railroads having adjacent track sections separated by insulated joints, code transmitting means for applying code pulses to the rear track section, a code following track relay having circuit connections to the track rails of the forward track section, contact means governed by said code transmitting means for opening said circuit connections for said track relay while an impulse is being applied to the rear track section, whereby said track relay may not be energized by the code pulses alone applied to the rear track section in the event said insulated joints should become broken down, and means responsive to the intermittent energization of said track relay by other legitimate code pulses for rendering said contact means ineffective.

4. In a coded track circuit signaling system in which driven code pulses are transmitted in each of a succession of track sections separated by insulated joints, code transmitting means associated with the leaving end of each section for applying code pulses to that section in accordance with traffic conditions in the next adjacent section in advance, a code receiving track relay normally connected across the entering end of each track section, isolating means associated with each track relay and acting to isolate that track relay from its track section only during the time when the associated code transmitting means for the adjacent section next in the rear is applying a code pulse to such rear section, and means associated with each track relay and responsive to its intermittent operation for rendering said associated isolating means ineffective, and thereby render that track relay responsive to code pulses in its track section independently of the associated code transmitting means for said adjacent track section.

5. In a coded track circuit signaling system for railroads, two adjacent track sections separated by insulated joints, code transmitting means for applying time-spaced code pulses of different polarities to the rear track section, a polar-responsive code receiving track relay associated with the forward track section, circuit means governed by said code transmitting means for connecting said track relay across the rails of its section only during the time spaces between the code pulses applied to the rear track section, and means governed by said track relay and rendered effective only in response to code pulses in said forward track section for connecting said track relay to its track section independently of the operation of said code transmitting means.

6. In a coded track circuit signaling system for railroads, a forward and a rear track section separated by insulated joints, code transmitting

means for applying time spaced code pulses of different polarities to the rear track section, a polar-responsive code receiving track relay associated with the forward track section, contact means for disconnecting said track relay from the rails of its section only during the time the code pulses are applied to the rear track section, decoding means governed by said track relay so as to be distinctively responsive to the different code rates repeated by said track relay, means for controlling said code transmitting means by said decoding means so as to transmit different code rates selected in accordance with the code rate then governing said decoding means, and means controlled by said decoding means for directly connecting said track relay across the rails of its section independently of said contact means.

7. In a coded track circuit signaling system for railroads, a forward track section separated from a rear track section by insulated joints, a signal governing the passage of traffic from the rear track section into the forward track section, code transmitting means associated with said signal for applying code pulses of different polarities to said rear track section, said pulses being of relatively short duration and separated by time spaces, a code following track relay of the two-position magnetic stick type associated with said forward track section, circuit means for connecting said track relay across the rails of its section, said circuit means including contacts governed by said code transmitting means and effective to complete said connection only during the time spaces between the impulses applied to the rear track section, decoding means distinctively controlled by the operation of said track relay to its opposite positions in accordance with the different rates of the code pulses in the forward track section for governing the indications of said signal, said decoding means responding to each distinctive rate independently of the momentary disconnection of its associated track relay, and means controlled by said decoding means for maintaining said track relay connected to the rails of its section independently of said contacts when a particular code rate is received by said track relay.

8. In a coded track circuit signaling system for railroads, a forward track section separated from a rear track section by insulated joints, a signal governing the passage of traffic from the rear track section into the forward track section, a code following track relay of the two-position magnetic stick type normally connected across the rails of said forward track section, decoding means governed by the operation of said track relay alternately to opposite positions in accordance with different code rates for governing the indications of said signal, code transmitting means associated with said signal for applying code pulses of opposite polarities alternately to said rear section at different code rates as selected by said decoding means, isolating means controlled by said code transmitting means for isolating said track relay from its track section during the application of each code pulse to said rear track section, and means controlled by said decoding means for rendering said isolating means ineffective only in response to the reception of a particular code rate by said track relay.

9. In a coded track circuit signaling system having a plurality of track sections separated from each other by insulated joints, coded track circuit apparatus associated with each section

comprising driven code transmitting means at the leaving end of the section for transmitting driven code pulses of opposite polarities alternately at different selected rates, driven code receiving means at the entering end of the track section distinctively responsive to the different rates of driven code, and acting to select the rate of the driven code in the next adjacent track section, inverse code transmitting means associated with said code receiving means for transmitting an inverse code pulse of a predetermined polarity on each even numbered driven code pulse, inverse code receiving means at the leaving end of the section comprising a polarized relay of the two-position type operated to one position by each inverse code pulse, and local means effective during each odd numbered driven code pulse to operate said inverse code relay to its other position.

10. In a coded track circuit signaling system for adjacent track sections separated by insulated joints, code transmitting means for applying code pulses of different polarities to the rear track section, a code following track relay for the forward track section, means including contacts governed by said code transmitting means for disconnecting said track relay from the track rails of said forward track section only while code pulses are being applied to the rear track section, means for actuating said code transmitting means at certain different code rates under different traffic conditions, and means responsive to an intermittent energization of said track relay at a code rate different from said certain code rates for the rear track section for connecting said track relay to the forward track section independently of the operation of said code transmitting means.

11. In a coded track circuit signaling system for railroads having a plurality of track sections separated by insulated joints, code transmitting means associated with each track section for applying driven code pulses to the exit end of the next track section in the rear at a caution or a clear code rate dependent upon traffic conditions, a code following track relay for the entrance end of each track section normally connected to the track rails of that track section, isolating means governed by the associated code transmitting means for isolating the track relay of the corresponding track section while that transmitting means is acting to apply code pulses to the next track section in the rear, and relay means responsive to the intermittent operation of the track relay for a given track section only at a clear code rate for rendering the associated isolating means ineffective, said clear code rates for adjacent track sections being different, whereby the means isolating a track relay from the code pulses applied to the next track section in the rear cannot be rendered ineffective by the clear code rate for that rear track section.

12. In a coded track circuit for railroads, a track battery, a limiting resistance, code transmitting means for pole-changing said track battery in series with said limiting resistance across the track rails at one end of a track section to provide driven code pulses of alternate polarity, means associated with the other end of said track section and governed by said driven code pulses for transmitting inverse code pulses of a fixed polarity during the intervals following the driven code pulses of one particular polarity, an inverse code following track relay of the two-position magnetic stick type, and means gov-

erned by said code transmitting means for alternately connecting said track relay to the track section and across a selected part of said limiting resistance, said track relay being operated to one position by said inverse code pulses and to the other position by the voltage drop across said selected part of the limiting resistance only when said transmitting means is operated to apply a driven code pulse of said particular polarity.

13. In a coded track circuit signaling system for railroads having a plurality of track sections separated by insulated joints, code transmitting means at one end of each track section and including intermittently operated coding contacts for applying code pulses of alternate polarity at the beginning and the end of each closing operation of said coding contacts, a code following track relay of the magnetic stick type at the other end of each track section intermittently operated by said driven code pulses of alternate polarity, and inverse code transmitting means for said other end of each track section governed by said code following track relay and effective to apply an inverse code pulse immediately following every other driven code pulse, said inverse code pulses being of a fixed polarity, whereby the code following track relay of a track section cannot be improperly operated by the inverse code pulses for the track section next in the rear in the event the insulated joints separating these track sections are broken down.

14. In a coded track circuit signaling system for railroads having a plurality of successive track sections each separated from the adjacent track sections by insulated joints, coded track circuit apparatus associated with each track section comprising driven code transmitting means associated with the leaving end of each track section for transmitting driven code pulses of opposite polarities alternately at different selected code rates, code receiving means at the entering end of each track section responsive only to the driven code pulses of opposite polarities alternately and distinctively controlled in accordance with the rate of reception of such pulses for selecting the code rate to be transmitted in the next adjacent section to the rear, said means also being effective on alternate impulses for transmitting an inverse code pulse of a particular polarity during the succeeding time space, inverse code receiving means at the leaving end of each track section responsive to each inverse code pulse in that track section so as to be operated to one position and controlled by the succeeding driven code pulse so as to be operated to the opposite position, and means controlled by the driven code transmitting means associated with the leaving end of each track section for disconnecting the code receiving means for the next adjacent track section in advance during the application of each driven code pulse to such leaving end of the track section unless legitimate code pulses are being received in said advance track section, whereby said code receiving means for any track section is immune to either driven or inverse code pulses applied to the track section in the rear even though the separating insulating joints should break down.

15. In a coded track circuit signaling system for a succession of track sections separated from each other by insulated joints, signals for governing traffic in one direction through said section, one signal at the entrance to each track section, coded track circuit apparatus associated with each signal comprising driven code trans-

mitting means for applying time spaced pulses of opposite polarities alternately to the track section in the rear of the associated signal, a code receiving track relay associated with the section in advance of the signal, decoding means responsive to the operation of said track relay to its opposite positions for controlling the indications of said signal and selecting the rate of code pulses applied by the associated code transmitting means, inverse code transmitting means associated with each track relay and controlled thereby so as to transmit an inverse code pulse of a particular polarity following the reception of every other driven code pulse having a particular polarity, an inverse code receiving track relay connected across the track rails of the rear section during the time spaces between successive impulses and operated to one position by the reception of an inverse code pulse, and means for causing said inverse code track relay to be operated to the opposite position during the trans-

mission of each driven code pulse of a polarity opposite to said particular polarity.

16. In a coded track circuit signaling system in which driven code pulses of opposite polarities alternately are transmitted in each track section, means for transmitting inverse code pulses of a particular polarity in each track section, code receiving means associated with the entering end of each track section responsive to the opposite polarities of the driven code pulses of its own section but being isolated therefrom during the transmission of the code pulses in the next adjacent track section to the rear, whereby the code receiving means cannot respond to the code pulses in the rear track section in the event the separating insulated joints break down, and whereby said inverse code pulses of only a particular polarity cannot operate said code receiving means to its opposite positions.

NEIL D. PRESTON.
